UNITED STATES PATENT OFFICE.

JOHN K. GRAHAM AND GEORGE A. RASMUSSEN, OF ROANOKE, VIRGINIA.

SPACING DEVICE FOR PUNCHING, RIVETING, SHEARING, AND OTHER MACHINES.

1,081,826.

Specification of Letters Patent. Patented Dec. 16, 1913.

Application filed June 20, 1913. Serial No. 774,854.

To all whom it may concern:

Be it known that we, JOHN K. GRAHAM and GEORGE A. RASMUSSEN, a citizen of the United States and a subject of the Emperor 5 of Germany, respectively, residing in Roanoke, county of Roanoke, State of Virginia, have invented certain Improvements in Spacing Devices for Punching, Riveting, Shearing, and other Machines, of which the 10 following is a specification.

This invention relates to certain improvements in the means used for spacing holes a given distance apart in machines for punching plates or in machines for cutting blanks 15 from a plate, the cuts being arranged a predetermined distance apart.

The invention can also be used for riveting or for any purpose where points are to be spaced a given distance apart.

20 One object of the invention is to construct the mechanism so that it will space accurately and automatically.

A further object of the invention is to dispense with as many joints as possible so that 25 in the event of wear there will be very little, if any, adjustment required.

A still further object of the invention is to utilize a magnetic clutch in connection with fluid mechanism which actuates a table 30 upon which a plate, or other material, is placed in front of a punching or other machine.

Another object of the invention is to provide a fixed stop and a movable abutment 35 which allows the mechanism to travel in the space between the fixed stop and the movable abutment.

The invention also relates to certain details which will be fully described herein- 40 after.

In the accompanying drawings: Figure 1 is a plan view, partly in section, of our improved spacing device; Fig. 2 is a longitudinal sectional view; Fig. 3 is an enlarged 45 view of part of Fig. 2; Fig. 4, is an enlarged view of the operating lever and clamp; Fig. 5 is a transverse sectional view on the line $a-a$, Fig. 3, and Fig. 6 is a view of a modification.

50 Referring to the drawings, 1 is the base of the spacing device on which is mounted a pneumatic cylinder 2.

3 is the slideway for the sliding abutment 4.

55 5 is the slideway for the cross head 6 and

on one end of the base is a fixed abutment 7.

8 is a shaft on which is a gear wheel 9 meshing with a rack 10 secured to the bed 11 of a punching or cutting machine. While 60 we have shown the gear wheel 9 meshing directly with the rack 10, the mechanism between the shaft 8 and the bed 11 may be varied according to circumstances and a train of gears may be used instead of the 65 rack and gear wheel illustrated in the drawings.

On the shaft is a magnetic clutch 12, of any suitable type, having one element secured to the shaft and another element 13 70 which is provided with a head 14. Connected to the cross head 6 is a rod 15 which is forked, as shown in Fig. 1, and which embraces the head 14 of the movable element of the magnetic clutch so that motion imparted 75 to the cross head will turn the clutch 12 and the shaft 8, and, consequently, the table or other element of the machine to which it is connected.

Mounted in the cylinder 2, which is a 80 pneumatic cylinder in the present instance, is a piston 16 having a rod 17 projecting on each side of the piston and extending through both heads 18 and 19 of the cylinder. One end of the rod 17 is attached to 85 the cross head while the other end has a bumper 20, which abuts against a plate 21 secured to the sliding abutment 4. In the head 18 of the cylinder is a stuffing box 22 and, in the present instance, a tubular extension 23 of the piston 16 extends through a stuffing box 24 in the head 19, but the constriction and arrangement of the cylinder and its piston may be modified, as desired. 90

25 is a valve chest and 26 and 27 are ports 95 leading from the chest to each end of the cylinder 2.

28 is a valve having a stem 29.

30 is an air inlet passage communicating 100 with both ends of the chest 25, as shown in Fig. 3. This valve may also be modified, if desired.

31, 31 are two cushion cylinders having pistons 32 therein connected by a rod 33 to an arm 34 on the cross head 6. In the pistons 32 are passages 35 to allow the liquid in the cylinder to pass from one side thereof to the other and there is a by-pass pipe 36 connected to both ends of each cylinder. In the by-pass pipe is a valve 37 which can be 105 110

turned to regulate the amount of liquid flowing from one side of the piston to the other through the pipe so that the travel of the cross head 6 can be regulated by the movement of said valve 37.

In order to allow the cross head to return to its normal position at a greater speed than that at which it moved forward, we provide pipes 38 connected to both ends of each cylinder 31 and in each pipe is a check valve 39 which allows the liquid to flow freely in one direction, but checks the flow of liquid in the opposite direction. It will thus be seen that the forward movement of the cross head 6 from the fixed abutment 7 toward the movable abutment 4 can be regulated by the valves 37 in the by-pass pipe 36 of the cylinder 31 but, on the return movement, the check valves will open and will allow the cross head 6 to return quickly to its normal position.

40 is a gage lever pivoted, in the present instance, to a frame 41, although it may be pivoted to any fixed point according to the type of machine to which the device is attached. This lever is connected to the sliding abutment 4 by means of a connecting rod 42.

43 is a segment having graduations thereon, as shown, and on the lever 40 is a pneumatic clamp 44 consisting of a cylinder 45, a plunger 46, and two cam levers 47 pivoted to the lever 40 and connected to the plunger 46. These cam levers are arranged to grip the segment 43 when there is pressure in the cylinder 45 but as soon as the pressure is released a spring 48 withdraws the cam levers so that the lever 40 can be turned on its pivot 41. The upper edge of the segment is notched, in the present instance, as at 49, and pivoted to the lever 40 is a spring latch 50 which is arranged to enter one of the notches in the segment so as to hold the lever 40 in the position to which it is adjusted until the pneumatic clamp 44 positively grips the segment.

In the present instance, the cylinder 45 is connected by a hose or pipe 51 to the forward end of the cylinder 2. When air is admitted through the piston 26 into the forward end of the cylinder it passes through the tube and actuates the clamp so as to firmly lock the lever 40 in the position to which it is set just prior to the cushion 20, on the piston rod 17, striking the abutment 4, which is locked in position by the lever 40 by setting said lever to any position prior to the admission of air. On actuating the valve 28, the cross head 5 moves the table, or other device to which it is connected, a given distance according to the lost motion between the fixed abutment 7 and the end of the cross head 6, as limited by the movable abutment 4.

52 is a push switch located at the hand grip of the lever 40. This switch is con-

nected to the magnetic clutch in any suitable manner. When the operator commences to move the lever 40, he can actuate the switch to connect the two elements of the clutch. The switch may be so arranged that it can be opened again to release the mechanism of the clutch or it may be held by the operator during the movement of the lever.

We prefer to use a magnetic clutch, as it can be so arranged that it will grip the elements to be moved prior to the movement of the actuating element. The type of magnetic clutch used may be varied without departing from the essential features of the invention.

In some instances magnetic clutches may be employed where the parts are gripped prior to the rotary movement and ratchet mechanism (which would be substantially a clutch) may be used for moving the shaft instead of a clutch.

In the majority of mechanical clutches, as now constructed, there is a slight slip which makes them undesirable for use in connection with an accurate spacing device.

In Figs. 1 and 2, we have illustrated a fixed cylinder and a movable abutment but, as illustrated in Fig. 3, the cylinder may be arranged to slide and is directly connected by a rod 42^a to the lever 40^a. The piston 16^a may be connected to the cross head 6^a in the ordinary manner and may abut against the rear end of the cylinder 2^a forming the movable abutment which is similar to the sliding abutment 4.

We claim:

1. The combination in a spacing device, of a clutch; an operating shaft on which the clutch is mounted; a table geared to the said shaft; a base; a cylinder; a piston in the cylinder; a cross head connected to the cylinder; an adjustable lever; a movable abutment connected to the said lever for limiting the movement of the cross head in one direction; and a fixed abutment for limiting the movement in the opposite direction.

2. The combination of a shaft geared to the mechanism to be actuated; a clutch on the shaft; a cylinder; a piston in the cylinder; a rod attached to the piston, said rod being connected to one element of the clutch, the other element of the clutch being mounted on the shaft; a fixed abutment to limit the movement of the piston in one direction; an adjustable abutment; and means for locking said abutment, the adjustable abutment limiting the movement of the piston in the opposite direction.

3. The combination of a base; a cylinder thereon; two slideways on the base; a cross head mounted in one slideway; an adjustable abutment mounted in the other slideway; a piston in the cylinder; a rod connecting the piston with the cross head, said

rod being arranged to abut against the adjustable abutment; a fixed abutment on the base with which the cross head comes in contact when moving in one direction; a shaft 5 connected to the mechanism to be operated; a clutch on the shaft, one element of the clutch being secured to the shaft; and means for connecting the other element to the cross head.

10 4. The combination of a base; a cylinder thereon; a piston in the cylinder; two slideways on the base; a cross head mounted in one slideway; an adjustable abutment mounted in the other slideway; a fixed abutment in the path of the cross head; a rod 15 connected to the piston in the cylinder and to the cross head and having a bumper arranged to come in contact with the adjustable abutment; a pivoted lever; means for locking the lever in the position to which it is adjusted; a rod connecting the lever with the adjustable abutment; a shaft connected to the element to be adjusted; a clutch on the shaft, one part of the clutch being attached thereto; and means connecting the other part of the clutch to the cross head so that the fixed abutment will limit the movement of the cross head in one direction, the adjustable abutment limiting the movement 20 in the opposite direction.

5. The combination in a spacing device, of a base; a fixed abutment; an adjustable abutment; means for adjusting said latter abutment; a cylinder secured to the base; a piston in the cylinder; a cross head arranged to come in contact with the fixed abutment; a shaft; a clutch on the shaft connected to the cross head; a second cylinder; a piston therein, also connected to the 30 cross head; and a by-pass in the said cylinder.

6. The combination in a spacing device, of a fixed abutment; an adjustable abutment; means for adjusting and setting said latter abutment; a cylinder; a piston in the cylinder; a rod secured to the piston; a cross head to which the piston rod is attached, said cross head being arranged to strike the fixed abutment, the end of the piston rod 40 being arranged to strike the adjustable abutment; a valve for admitting fluid to the cylinder; two additional cylinders having passages; rods attached to the cross head; a by-pass pipe communicating with both ends of each cylinder; and a regulating valve in the by-pass pipe for regulating the movement of the main piston rod and its cross head.

7. The combination in a spacing machine, of a base; a fixed abutment thereon; an adjustable abutment also on the base; a lever connected to the adjustable abutment; means for adjusting and locking said lever; a cylinder; a piston therein; a rod extending through the cylinder; a cross head secured 50 to one end of the rod, the other end of the

rod being arranged to come in contact with the adjustable abutment; a valve for regulating the passage of liquid to the cylinder; a shaft connected to the mechanism to be spaced; a clutch mounted on the shaft; 70 means connecting the clutch to the cross head; a second cylinder having a piston therein and a rod, said rod being connected to the cross head; a by-pass pipe communicating with both ends of the said cylinder; 75 a regulating valve in said passage; and a second passage communicating with both ends of the cylinder and having a check valve therein.

8. The combination in a spacing device, 80 of a base; a fixed abutment thereon; an adjustable abutment also on the base; a cylinder; a piston therein; a piston rod; a cross head to which the piston rod is connected; said cross head being arranged to come in 85 contact with the fixed abutment, the opposite end of the rod being arranged to come in contact with the adjustable abutment; a pivoted lever; a rod connecting the lever with the adjustable abutment; a segment; 90 a clutch for locking the lever in the position to which it is adjusted; a clutch on the shaft; and means connecting the clutch with the cross head.

9. The combination in a spacing device, 95 of a base; a fixed abutment thereon; an adjustable abutment also on the base; a cylinder; a piston therein; a piston rod; a cross head to which the piston rod is connected, said cross head being arranged to 100 come in contact with the fixed abutment, the opposite end of the rod being arranged to come in contact with the adjustable abutment; a pivoted lever; a rod connecting the lever with the adjustable abutment; a segment; 105 a clutch for locking the lever in the position to which it is adjusted; a clutch on the shaft; means connecting the clutch with the cross head, the said segment having a serrated edge; and a latch on the lever engaging the serrations on the segment so that the lever can be locked in the position to which it is adjusted prior to being held by the clutch.

10. The combination in a spacing device, 115 of a base; a fixed abutment; an adjustable abutment arranged to slide on the base; a cross head, also arranged to slide on the base, and located so as to come in contact with the fixed abutment; a cylinder; a piston therein; a rod extending through the cylinder and connected to the cross head, said rod being arranged to come in contact with the adjustable abutment; a shaft; a clutch on the shaft; means connecting the clutch with the cross head; a lever; a rod connecting the lever with the movable abutment; a fluid operated clutch carried by the lever and arranged to engage the segment; a pipe leading from 120 125 130 135 140 145 150 155 160 165 170 175 180

the cylinder of said clutch to the main cylinder so that when liquid is admitted to the main cylinder the lever is clutched to the segment prior to the piston rod striking the 5 adjustable abutment.

11. The combination in a spacing device, of a magnetic clutch; an operating shaft on which one element of the clutch is mounted; a table geared to said shaft; a base; a fixed 10 abutment on the base; a cylinder; a piston in the cylinder; a cross head connected to the cylinder; means for connecting the other element of the magnetic clutch to the cross head; an adjustable hand lever; a movable

abutment connected to the said lever for 15 limiting the movement of the cross head in one direction; a fixed abutment for limiting the movement of the lever in the opposite direction; and a push switch on the lever connected to the magnetic switch. 20

In testimony whereof, we have signed our names to this specification, in the presence of two subscribing witnesses.

JOHN K. GRAHAM.
